UNITED STATES PATENT OFFICE

2,458,938

AUTOMATIC KEY CASE

Sydney Greenhow, Windsor, Ontario, Canada

Application May 10, 1946, Serial No. 668,938

3 Claims. (Cl. 70—456)

1

The invention relates to a key holder and more especially to a pocket key holder.

The primary object of the invention is the provision of a holder of this character, wherein keys can be held in groups, within a case therefor and a particular key can be readily and conveniently selected with ease and dispatch without disturbing the keys of other groups than that including the selected key desired, the holder being of novel construction and is unique in the assembly of its parts, so that in the working of the holder it will assure quick access thereto for the selection of a determined key in a particular group confined thereby.

Another object of the invention is the provision of a holder of this character, wherein keys can be readily placed therein and removed therefrom at will, the keys when held in the case being accessible from either side of the latter and from opposite areas thereof, without the projecting of all keys carried in the case.

A further object of the invention is the provision of a holder of this character, wherein it can be carried in a pocket of a garment, without damage thereto, resultant from wear and tear of the keys on the pocket, as is usual where the keys are strung on a ring or other like member, the case of the holder being an enclosure for the keys to prevent misplacement or loss thereof.

A still further object of the invention is the provision of a holder of this character, which is simple in construction, thoroughly reliable and effective in the purposes intended thereof, strong, durable, compact, possessed of few parts, neat in appearance, and inexpensive to manufacture.

With these and other objects in view the invention consists in the features of construction, combination and arrangement of parts as will be hereinafter more fully described, illustrated in the accompanying drawing, which discloses the preferred embodiment of the invention, and pointed out in the claims hereunto appended.

In the accompanying drawing:

Figure 1 is an end elevation of the holder constructed in accordance with the invention.

Figure 2 is a sectional view taken on the line 2—2 of Figure 1 looking in the direction of the arrows.

Figure 3 is a sectional view taken on the line 3—3 of Figure 1 looking in the direction of the arrows.

Figure 4 is a sectional view taken on the line 4—4 of Figure 2 looking in the direction of the arrows.

Figure 5 is a sectional view taken on the line 5—5 of Figure 2 looking in the direction of the arrows.

2

5—5 of Figure 2 looking in the direction of the arrows.

Figure 6 is a view similar to Figure 5 showing the case of the holder in a partially open condition.

Figure 7 is a side view of the case of the holder.

Similar reference characters indicate corresponding parts throughout the several views in the drawing.

- 10 Referring to the drawing in detail, the key holder constituting the present invention, comprises a pair of opposed outwardly bowed inherently springy elongated side panels 10, which match each other with the longer side edges arranged normally close and in parallel relation to each other to provide a key enclosing case which is identified generally at A.
- 20 The panels 10 have interposed therebetween at the longitudinal center thereof a sectional double loop-like coupling frame denoted generally at B, it involving longitudinally aligned separated key hanger loops 11 and 12 respectively, which at their outer ends are provided with entrance and release gaps normally closed by ball-like closure heads 13 terminally formed on reversely extended curved arms 14 of a divider web 15, which is located at the longitudinal center of the loops 11 and 12, and unitary with a cross strut 16 of the frame B, which is slightly less in length than the case A.

30 The panels 10 at their longitudinal median are loosely connected by rings 17 to the side runs 18 of the frame B at opposite sides thereof, so that pressure on the panels in the directions as indicated by the arrows in Figures 5 and 6 of the drawing, will open the case A selectively to either side of the web 15 and at reverse sides of the frame B, so that a selected group or groups of keys 19 hung on the loops 11 and 12 will become exposed and accessible for service or a determined key can be projected from the case A for use. The keys 19 are grouped on the loops 11 and 12 respectively, as best seen in Figure 2 of the drawing.

40 The keys 19 are inserted through and released from the gaps normally closed by the closure heads for engagement on or removal from the loops 11 and 12, which are inherently springy for latching engagement in the closure heads, as 50 should be apparent, the strut 16 being a rest for the bits of the keys 19, when the latter are encased within the case A.

What is claimed is:

1. A holder of the kind described, comprising a double loop like frame having entrance and

release gaps to and from the loops thereof, a web dividing the loops of the frame and having closure terminals for the gaps, and outwardly bowed flexible panels connected to the frame for encasing the latter and giving access thereto when external pressure is applied thereto.

2. A holder of the kind described, comprising a double loop like frame having entrance and release gaps to and from the loops thereof, a web dividing the loops of the frame and having closure terminals for the gaps, and outwardly bowed flexible panels connected to the frame for encasing the latter and giving access thereto when external pressure is applied thereto, and loose ring connections between the panels and the said frame.

3. A key case comprising a cross strut, substantially parallel spring arms attached to said strut, said spring arms terminating in opposed key-receiving portions, said portions being spaced from each other to form a gap between which keys may be inserted and threaded onto said key-receiving portions, releasable means

coupling said key-receiving portions to close said gap for removably retaining the keys on said portions, resilient panel members extending lengthwise of said parallel spring arms and curved about said arms toward each other whereby said panel members are adapted to contact each other, and means pivoting said panel members to said spring arms, whereby pressure upon said panel members at one side of said spring arms will cause said panel members to spread apart at the opposite side of said spring arms to expose the keys.
